UNITED STATES PATENT OFFICE.

LOREN G. WEBB, OF FORT ATKINSON, WISCONSIN.

COW-TAIL HOLDER.

No. 889,836.

Specification of Letters Patent.

Patented June 2, 1908.

Application filed October 17, 1907. Serial No. 397,870.

To all whom it may concern:

Be it known that I, LOREN G. WEBB, a citizen of the United States, residing at Fort Atkinson, in the county of Jefferson and 5 State of Wisconsin, have invented certain new and useful Improvements in Cow-Tail Holders; and I do declare the following to be a full, clear, and exact description of the invention, such as will enable others skilled in 10 the art to which it appertains to make and use the same.

This invention relates to improvements in cow tail holders.

The object of the invention is to provide a 15 device of this character by means of which the cow's tail may be held and prevented from being switched into the face of the person milking.

A further object is to provide a cow tail 20 holder which will be simple, strong and durable in construction, efficient and reliable, and well adapted for the purpose for which it is designed.

With these and other objects in view, the 25 invention consists of certain novel features of construction, combination and arrangement of parts, as will be more fully described and particularly pointed out in the appended claims.

30 In the accompanying drawings,—Figure 1 is a perspective view of the holder; Fig. 2 is a longitudinal sectional view of the same; Fig. 3 is a view similar to Fig. 1, showing a different form of fastening device for securing the holder in place.

Referring more particularly to the drawings, 1 denotes the holder which consists of a body portion in the form of a curved sheet metal plate 2, preferably formed of galvanized or other non-corrosive metal. Arranged 40 on the upper side of the plate 2 is a bail-shaped spring-clamping member 3, one end of which is suitably secured to the plate adjacent to one end of the same, as shown at 4. 45 The clamping spring 3 is adapted to coact with the plate to hold the end of the cow's tail when engaged therewith.

In the plate adjacent to each end are formed short transversely disposed slits, the 50 metal between which is pressed downwardly to form strap guides or loops 5, through which is adapted to be inserted a fastening strap 6. The strap 6 is disposed beneath the plate, and is adapted to be passed around the 55 leg of the person milking and buckled or otherwise secured, thereby firmly holding the plate 2 and the clamping member in

proper position to receive the switch or end of the cow's tail.

In Fig. 3 of the drawings is shown a different form of fastening device for the plate, said fastening device being shown in this instance as consisting of a bow spring 7, which is suitably secured to the underside of the plate. The ends of the spring 7 are adapted 60 to be engaged with the leg of the person milking, thus firmly securing the plate in place.

From the foregoing description, taken in connection with the accompanying drawings, the construction and operation of the invention will be readily understood without requiring a more extended explanation.

Various changes in the form, proportion and the minor details of construction may be resorted to without departing from the 75 principle or sacrificing any of the advantages of this invention, as defined in the appended claims.

I claim as my invention:

1. A cow tail holder comprising a curved 80 sheet metal plate, a clamping spring secured at one end of said plate and adapted to coact therewith to hold the end of the cow's tail, and a fastening strap slidably connected with the underside of the plate and adapted 85 to buckle around the leg of the person milking to hold said plate in position, substantially as described.

2. A cow tail holder comprising a plate, a bail-shaped clamping member formed from 90 a single piece of spring wire bent midway between its ends into the form of a bail or loop, the ends of which are inserted through apertures formed in one end of said plate, said ends being bent over and clenched to the end 95 of the plate, whereby said spring clamp is secured to the latter, spring coils formed in the ends of said loop or bail adjacent to the points where the same is secured to the plate, whereby the bail-shaped end of the clamping member is held down into engagement with said plate, and co-acts therewith to form the tail-engaging clamp, and an attaching strap secured to the other side of said plate, whereby the latter is adapted to be attached to the leg of the person milking. 100

In testimony whereof I have hereunto set my hand in presence of two subscribing witnesses.

LOREN G. WEBB.
